17 Claims. (Cl. 175—363)

The present invention relates to vapor electric discharge devices having anode-control grids, and it has for its object to provide improved means for the regulation of the rectified voltage as a function of the output current, or of the current as a function of the power output or of the current supplied by any other apparatus coupled in parallel.

The invention provides for the automatic regulation of a discharge device employed as rectifier, particularly in compounding to give constant voltage at varying output, over-compounding, under-compounding, operation at constant current with varying power, parallel working, and connection to a supply system fed by one or more other sources of continuous current. This regulation is effected automatically by the use of an auxiliary generator or exciter of the type having three field windings, one being a shunt winding and the others acting in opposition to one another, the voltage of the auxiliary generator or exciter being combined with the alternating bias voltage applied to the anode-control grids so as to render the rectifier independent of its own normal characteristic and of the variations of the external or output circuit and to endow it with the desired characteristic, which may be that of a reference machine of very small power.

In general, the alternating voltage applied to the control grids will have the same frequency as the anode voltage, but it may be of different frequency. The regulation of the rectifier is rendered independent of possible variations of the grid blocking or biasing voltage. It is possible to obtain a very high accuracy of regulation by the use of a series motor included in the grid circuit and operating as a negative resistance.

The invention is hereafter described with reference to the accompanying drawings, in which:—

Fig. 1 is a diagram illustrating a known method of regulating the moment of ignition in a rectifier of the vapor electric discharge type.

Fig. 2 is a diagram illustrating the normal operation of a three field winding exciter, of which the essential parts are shown in Fig. 3.

Fig. 4 is a diagram corresponding to Fig. 2, but illustrating the operation of the three field winding exciter as applied in the present invention.

Fig. 5 represents diagrammatically one arrangement for carrying out the invention.

Fig. 6 is a diagram showing the relation between the rectifier voltage and output current.

Figs. 7, 8, 9, 10 and 11 represent diagrammat-

ically other arrangements for carrying out the invention.

Various arrangements have already been proposed for regulating electrical rectifiers of the vapor electric discharge type with anode-control grids, by utilizing a grid exciting voltage composed of an alternating voltage E_{ga} of the same frequency as the anode voltage, and a superposed continuous voltage E_{gc} variable in relation to the cathode potential; see Fig. 1. The moment of ignition of an anode is more or less retarded according to the value of the continuous component E_{gc} of the biasing voltage E_{ga} , which represents the resultant alternating potential of the grid in relation to the cathode potential. The corresponding anode ignites when the grid potential reaches the value 0, this being only approximately correct, but sufficient for the present explanation. When the continuous component $E_{gc}=0$, the anode ignites at A, so that if the vertical line xy passing through the natural point of ignition of the anode be taken as axis of reference for the angles of ignition, the ignition angle is represented by α_0 . Now if the continuous component E_{gc} of the biasing voltage be given a certain value $E^{1}gc$, regarded as positive when it tends to displace the resultant voltage curve E_{ga} upwardly in the direction of the arrow, the ignition angle becomes α_1 which is less than α_0 .

In particular, it has been sought to utilize this method of grid control in order to secure an automatic regulation of the continuous voltage E_c as a function of the output current I_c supplied by the rectifier, by variation of the continuous voltage E_{gc} applied to the control grids, according to a definite law $E_{gc}=f(I_c)$.

It has been noted that in a vapor electric discharge rectifier with movable cathodic spot, which is the case for apparatus of large power, the blocking or biasing voltage for a given anode voltage is variable. It depends not only on the position of the cathodic spot, but likewise on the temperature of the rectifier (in particular on the temperature of the anodes), on the state of ionization of the vapor in the vicinity of the anodes, on the magnitude of the continuous current output and on the pressure. This inconvenience has the direct consequence that the regulation of the continuous voltage by the method mentioned above loses all precision for the relationship $E_{gc}=f(I_c)$ which is imposed on the continuous voltage exciting the grid. The variation of the continuous voltage given by the rectifier as a function of the continuous current output, shows

a relation which is quite different from that which it is desired to obtain.

The present invention has for its object to remedy this inconvenience and to obtain any desired relationship either of the continuous voltage E_c to the load, or of the output current I_c to the continuous current power output, or of the current I_c to the current supplied by any other apparatus (whether ionized vapor rectifiers or rotary machines) coupled in parallel with the rectifier under consideration.

The grid control voltage is still constituted by an alternating voltage E_ga , of the same frequency as the anode voltage, and a superposed variable continuous voltage E_gc , but the latter can assume automatically such value as is necessary at a given moment for either the rectified voltage E_c or the continuous output current I_c to conform with the desired relationship. In this way the operation becomes independent of variations of the grid blocking or biasing voltage.

Before entering into details of the invention, it may be explained that it is based upon the well-known properties of the three field winding exciter, as employed for example with continuous current traction motors and usually driven at constant speed. One of the exciter field windings is always shunt and it is regulated in such a way that its resistance line $d'Od$ coincides with the straight part A^1OA of the no-load characteristic B^1OB corresponding to the equation $e=f(n i)$, where e is the exciter voltage and $n i$ the resultant ampere turns of field excitation; see Fig. 2.

For a more complete understanding of the invention, it is desirable to recall the principle of operation of an exciter of this kind. Fig. 3 represents an exciter E driven at constant speed by a suitable motor, not shown in the drawings. This exciter feeds an external circuit C , the precise nature of which may for the moment be considered as immaterial.

Let a be the shunt field winding of the exciter E , and b and c two other field windings which are subject to the condition that their respective ampere-turns act in opposition. If the winding a has n_a turns, and i_a designates the current flowing in this winding, the shunt ampere-turns are represented by $n_a i_a$. If the winding b has n_b turns, and i_b designates the current flowing in this winding, its ampere-turns are represented by $n_b i_b$. Similarly, if the winding c has n_c turns, and i_c designates the current flowing in this winding, its ampere-turns are represented by $n_c i_c$.

Suppose that the following condition is fulfilled:—

$$n_b i_b = n_c i_c \quad (1)$$

then owing to the regulation of the shunt field as indicated above, and the equality of the opposing ampere-turns ($n_b i_b$ and $n_c i_c$), the voltage e which the exciter can produce is indeterminate. For, considering the general equation, expressed in absolute values,—

Resultant ampere-turns=

$$(n_a i_a) + (n_b i_b) + (n_c i_c)$$

It follows from the previous Equation (1) that the point of operation of the exciter E may be located anywhere along the line A^1OA in Fig. 2, whatever be the absolute value of $n_b i_b$ or $n_c i_c$.

Assume that at a given moment this point of operation is at F on the corresponding line A^1OA in Fig. 4, and that for some reason there is an

inequality between the respective ampere-turns $n_c i_c$ and $n_b i_b$, the latter for example being the greater and the difference being Δn_i ; the voltage e of the exciter will increase up to the point D .

Now it will be supposed that there exist between the circuit C and the field winding c electrical connections such that to a positive increase Δe of the exciter voltage there corresponds a positive increase Δi_c of the current i_c flowing through the field winding c , this increase taking place without any delay or lag.

In these conditions the voltage e will not reach the point D because the Equation (1) will be re-established when the voltage e reaches the point G for example, G being still located on the straight portion A^1OA of the exciter characteristic. It will be understood that the possible variation of the exciter voltage e between the points A^1 and A must be sufficient for the complete regulation of the current i_c , this requirement being only a matter of machine design.

It may be remarked, on the other hand, that in the conditions assumed, the point G is well defined. In fact, if the voltage e took up another position at G^1 near the point G , there would result an increase of the field current i_c and the Equation (1) would no longer be satisfied. According to the explanation given above, the voltage e will tend to move to the point G , the only one at which equilibrium is possible.

Before proceeding further, it is necessary to note that no hypothesis has been set up as to the nature of the electrical connections which can exist between the circuit C and the winding c . It is desirable to remark however that in all the applications of the three-field winding exciter hitherto suggested, the exciter controls the external circuit C in a purely electro-dynamic manner, which means that the exciter E acts by feeding into the circuit C a variable current i_c determined by the equation:

$$e + e_c + R_c i_c = 0;$$

where e_c represents the back E. M. F. of the circuit C , R_c the resistance of this circuit and e the voltage of the exciter E .

On the contrary, in the applications which are now to be considered, the circuit in which the exciter E is inserted possesses no back E. M. F. balanced by the voltage e of the exciter. The function of the latter consists in modifying the relative potential of a point in the control system C in a purely electrostatic manner, which is new in the art, of utilizing the three field winding exciter described above.

Fig. 5 represents one arrangement in which the principle of the three-field winding exciter is applied; this arrangement allows of maintaining constant the continuous voltage E_c of the rectifier, while the value of the output current I_c can vary between O and I_{CN} (Fig. 6). In Fig. 5, R represents the ionized metallic vapor rectifier, having six anodes a_r provided with control grids g ; T represents the transformer feeding six-phase current to the anodes of the rectifier; H represents the six-phase potential phase-shifter feeding the anode-control grids g by way of resistances r ; E represents the auxiliary generator or exciter with three field windings a , b and c ; and S is a shunt-wound exciter feeding the field winding b of the exciter E , the two machines E and S being coupled together mechanically and driven at constant speed by a suitable motor, not shown in the drawings.

The shunt field winding a of the exciter E is regulated as already explained with reference to Fig. 2.

The separately excited field winding b is traversed by a constant current at any given adjustment of the variable field rheostat rh of the exciter S .

The other field winding c is fed by the continuous voltage of the rectifier R .

10 The exciter E is to be connected between the cathode K of the rectifier and the neutral point O^1 of the phase-shifter H .

Assume for the moment that the exciter E is omitted and that the neutral point O^1 is connected directly to the cathode K . With the rectifier giving no current output, the phase-shifter H is regulated to produce such a lag in the ignition of the anodes that the rectified voltage E_c shall be equal to E_{CN} , that being the value 20 of the continuous voltage given by the rectifier for the full normal output I_{CN} according to the load-characteristic (see Fig. 6) of the transformer-rectifier group, when the grids are not energized; the angular displacement of the 25 phase-shifter H will be designated α_0 as already defined with reference to Fig. 1.

With the exciter E still out of the circuit of the phase-shifter H , but the field winding c connected to the terminals of the rectifier R , the 30 current i_b in the separately excited field winding b is regulated by means of the rheostat rh so as to obtain equality of the two quantities $n_c i_c$ and $n_b i_b$. The exciter E is then introduced into the circuit $O^1 K$, as shown in Fig. 5; as already 35 explained, the voltage e of the exciter must be nil. When a certain load is applied to the rectifier, the voltage E_c will tend to decrease according to its natural characteristic, so that the exciter field current i_c will tend to decrease also; 40 since the current i_b in the separately excited field winding b is maintained, the exciter E will begin to generate a voltage e which is applied to the control grids, causing a decrease of the anode ignition angle, from α_0 towards α^1 . The reduced ignition lag will bring about an increase 45 of the voltage E_c , causing it to resume the value E_{CN} at which $n_c i_c = n_b i_b$. Similar action will take place at any point up to the maximum value I_{CN} of the continuous current output.

50 It may be noted that there can be adopted a value of the angle α_0 different from that defined above, while yet retaining the same value for the field current i_b ; for example the ignition angle at nil output current may be less than α_0 and equal to α^1 ; the exciter voltage e for nil output current ($I_c=0$), instead of being nil, will then assume a negative value, for example G (Fig. 4), determined in such a way that the rectified voltage $E_c=E_{CN}$.

60 If the value of the field current i_b is modified by regulation of the rheostat rh , the continuous voltage E_c will still be maintained constant, whatever be the load, but it will assume a value E_c' different from E_{CN} . It will be seen therefore that the value of the voltage E_c remains constant at varying loads, and depends only on the value given to the field current i_b , which is kept constant at the selected value.

70 It is to be noted that the constant voltage E_c , given by this compound operation of the rectifier becomes independent of variations in the alternating supply voltage feeding the transformer T . Overcompounding or under-compounding of the voltage E_c , as a function of the 75 output current I_c , can be obtained by arrange-

ments analogous with that of Fig. 5; it is in fact only necessary to provide for the increase or the decrease of the separate excitation field current i_b when the output current I_c increases. This can easily be arranged, for example by providing a supplementary field winding upon the machine S , traversed by a current proportional to the output current I_c . The ampere turns of this supplementary field winding will be cumulative to the main field winding in the case of over-compounding, and differential in the case of under-compounding; the degree of over or under-compounding can be regulated by varying the proportions of the two field windings on the machine S . A plain reversing switch for one of the field windings will then allow of changing from over to under-compounding, and vice versa.

Any other means for producing a variation of the field current i_b as a function of the output I_c may be utilized for the same object.

A further application of the invention may be contemplated in which, instead of maintaining the voltage E_c constant, it is proposed to maintain the current constant when the power output varies. In this case, instead of connecting the 25 field coil c of the exciter to the terminals of the rectifier, it is so arranged as to be traversed by a current equal to or proportional to the output current I_c , as illustrated in Fig. 7, where L represents the continuous current system supplied 30 by the rectifier.

If the field current i_b supplied by the exciter S is constant, the current output I_c of the rectifier will be maintained constant and the voltage e of the exciter E will vary in magnitude and in sign 35 so as to regulate the voltage E_c of the rectifier according to the power required.

The angular displacement of the phase-shifter H is still assumed to be constant.

In order to modify the value of the output current I_c , it is only necessary to alter the value of the field current i_b .

A combination of the two preceding arrangements allows for the parallel working of two or more rectifiers, as well as any desired division of 45 loading between those apparatus, whatever be the load-characteristics of the machines (over-compounded or under-compounded).

Fig. 8 represents two groups of transformer-rectifiers working in parallel. The first rectifier 50 R_1 is provided with means analogous with Fig. 5 for regulating its voltage E_{C1} as a function of its output current I_{C1} for example maintaining its continuous voltage constant. The second rectifier R_2 is provided with means for regulating its 55 voltage E_{C2} to maintain its output current I_{C2} proportional to the current I_{C1} supplied by the first rectifier R_1 . In order to do this, the winding b of the exciter E_2 for the second rectifier R_2 is traversed by a current proportional to the output 60 current I_{C1} of the first rectifier. The distribution of the loads is regulated by means of adjustable resistances r_1 and r_2 . It will be seen that on one hand the voltage of the first rectifier R_1 will be maintained constant, as previously explained, and that on the other hand for a given power demanded by the supply system L , the exciter E_2 of the second rectifier will decide the proportioning of the two output currents I_{C1} and I_{C2} according to the relation fixed by the adjustment of the resistances r_1 and r_2 .

It has been assumed, in the case of Fig. 8, that the first rectifier R_1 (which may be regarded as the "pilot" rectifier of the sub-station) is provided with means for regulating its voltage E_{C1} .

It is evident that the parallel working of the rectifiers R_1 and R_2 could be carried out in the same way without the pilot rectifier R_1 being provided with means for regulating its voltage. The continuous voltage characteristic under load of the rectifier R_1 would then be determined by the leakage reactances of its transformer.

Any desired number of rectifiers controlled in this way may work in parallel; if this number be 10 n , it suffices to arrange $(n-1)$ rectifiers in a manner identical with that shown for R_2 in Fig. 8, the other rectifier being the pilot rectifier R_1 .

The improved system of control will allow of obtaining with equal efficiency the parallel operation of two or more rectifiers fed by independent alternating current supply systems, the frequencies of which may even be different.

The control system may easily be extended to cover the operation of rectifiers in parallel with 20 rotary continuous current machines, of which the load-characteristics may be of any kind. The electrical diagram of such an arrangement would be analogous with Fig. 8, but having the rectifier R_1 replaced by a continuous current generator of 25 rotary type.

Fig. 11 illustrates an arrangement of this kind, in which the rectifier R is connected in parallel with a rotary machine G , which may be a converter group or a mechanical rectifier. The 30 rectifier R is provided with means analogous with Fig. 5 for regulating its continuous output current I_{C1} while the generator G operates at constant voltage to supply the system L . The separately excited field winding b of the exciter E is 35 traversed by a current proportional to the output of the generator G , taken across a shunt Sh ; the other field winding c of the exciter is energized by the output current I_{C1} of the rectifier R . It will be seen that for a given power demanded by the 40 supply system L , the exciter E will decide the proportioning of the output currents from the generator and rectifier respectively, the two field windings b c balancing when the two output currents are in the correct relation.

The parallel running of rectifiers and rotary machines in the same sub-station may evidently be extended to the parallel working of two adjacent substations, of which one can be constituted in any desired manner, while the other is supposed to be constituted solely by rectifiers of the vapor discharge type. The power required for the control of the grids being very small, it becomes possible to have a single device for controlling the grids, all the grids being connected in parallel. In these conditions, the rectifier-substation can be controlled by the other substation by means of an exciter arranged in accordance with the diagram already considered for the exciter E_2 in Fig. 8; the currents circulating 55 in the field windings b_2 and c_2 would be proportional respectively to the currents supplied by the two substations.

The invention may also be employed for the 60 automatic connection of a rectifier to a supply system by means of a three field winding exciter in which the field winding b or c would be energized by the difference of potential between the voltage E_N of the supply system and the voltage E_C of the rectifier which is to be connected thereto. The principle of this operation of the exciter is explained in the specification of U. S. application Serial No. 545,557, F. Lejeune, filed June 19, 1931.

The arrangement represented diagrammatically in Fig. 5 for controlling the variation of the

continuous voltage as a function of the load may be insufficient in some cases, from the point of view of precision. In fact, if it is desired to effect the regulation of the continuous voltage E_C to within a few volts, it is necessary that with a small departure of the voltage E_C from the desired value, there shall be produced a large variation of the ampere-turns $n_c i_c$ so that the corresponding variation of the voltage e of the exciter E will likewise be large. For this reason, instead of making the ampere turns $n_c i_c$ depend upon the voltage E_C , they may be made to depend upon the difference between the rectifier voltage E_C and another voltage E_S , which may be termed the reference voltage, the sensitivity increasing as the difference $(E_C - E_S)$ approaches 0. If the difference $(E_C - E_S)$ is made equal to 0, the current i_b must be nil; the field winding b therefore becomes unnecessary and it can be suppressed. In other words, the differential action of the two opposing fields b c is replaced by a single field excited by a differential voltage.

Fig. 9 represents the general diagram of this novel arrangement. As in Fig. 5, the exciter E is connected to the terminal of the cathode K on 25 the one hand, and to the neutral point O^1 of the phase-shifter H on the other hand. The machine E possesses two field windings: a shunt winding a and an independent winding c . The exciter S is now placed in series with the field 30 winding c of the exciter E , the whole being connected to the neutral point O of the transformer T on the one hand and to the cathode K on the other hand; the continuous voltage E_S of the machine S is in opposition to the controlled voltage 35 E_C .

When $E_S = E_C$, the current circulating in the winding c is equal to 0. If E_C varies the winding receives a certain current i_c of which the value and the direction depend on the difference of voltage $(E_S - E_C)$, as well as on its sign, and on the resistance of the circuit $O - S - c - K$. If the difference $(E_S - E_C)$ is greater than 0, the exciter E produces a voltage e , which, when the regulation is correct, tends to diminish the ignition angle α 45 of the rectifier anodes and therefore to increase the value of the voltage E_C , as has already been explained. On the contrary, if the difference $(E_S - E_C)$ is less than 0, that is, negative, the field current i_c being reversed, the voltage e changes 50 sign and the inverse phenomenon is produced; the ignition angle α increases, causing the reduction in the value of the voltage E_C . It follows naturally from this arrangement that if it be desired to obtain an over-compounded or under-compounded characteristic of the continuous 55 voltage E_C , as a function of the load, it suffices to modify the voltage E_S of the machine S as a function of the output current I_C , as already explained.

For a given value of the difference of voltage $(E_S - E_C)$, the sensitivity of the system increases when the resistance of the circuit $O - S - c - K$ diminishes. This total resistance, which can be represented as X , can be reduced to as low a value 60 as desired, by placing in series in the circuit $O - S - c - K$ a small dynamo-electric machine having a series-wound field and playing the part of a negative resistance.

Fig. 10 represents an arrangement analogous 70 with that of Fig. 9, but provided in addition with a series motor S^1 coupled mechanically to the excitors E and S . This machine S^1 is connected in series with the exciter S and the independent field winding c of the machine E . The resistance X 75

represents the equivalent resistance of the circuit $O S^1 S c K$. By suitable dimensioning and regulation of this machine S^1 it is possible to produce at its terminals a voltage e_s of opposite sign and of the same absolute value as the drop of voltage (Xi_c) in the equivalent resistance X .

In conclusion, the use of the exciter having shunt and differential field windings in conjunction with the rectifier of the vapor electric discharge type, allows of obtaining any desired relation between the continuous voltage and current supplied, and of ensuring the parallel working either of a plurality of such rectifiers with one another or of one or more rectifiers with one or 15 more rotary machines, in such conditions as may be desired.

In all cases it is possible to render the controlled apparatus independent of their own characteristics and of any external variations (for 20 example, of the alternating current supply system) in order to impart to them the characteristic of a reference machine of very low power. This system is therefore very flexible, since it allows of substituting for the direct regulation 25 of machines of large power, that of an auxiliary group of small size, which is much easier and more economical.

What I claim is:—

1. Means for regulating a vapor electric discharge device provided with an anode, a cathode and a control grid, and having alternating potentials applied between said anode and cathode and control grid, with a continuous voltage component superposed on the alternating potential 35 between said control grid and cathode, comprising a dynamo-electric machine generating said continuous voltage component, a shunt field winding for said machine, other field-exciting means adapted to vary the total field excitation 40 of said machine, and an independent source of current, said other field exciting means being energized by said discharge device and said independent source of current, acting in opposition.

2. Means for regulating a vapor electric discharge device provided with an anode, a cathode and a control grid, and having alternating potentials applied between said anode and cathode and control grid, with a continuous voltage component superposed on the alternating potential 50 between said control grid and cathode, comprising a dynamo-electric machine generating said continuous voltage component, a shunt field winding for said machine, two other field windings for said machine, said other field windings 55 acting in opposition to one another, and an independent source of current, said other field windings being energized respectively by the output voltage of said discharge device and by said independent source of current.

3. Means for regulating a vapor electric discharge device provided with an anode, a cathode and a control grid, and having alternating potentials applied between said anode and cathode and control grid, with a continuous voltage component superposed on the alternating potential 65 between said control grid and cathode, comprising a dynamo-electric machine generating said continuous voltage component, a shunt field winding for said machine, two other field windings for said machine, said other field windings 70 acting in opposition to one another, and an independent source of current, said other field windings being energized respectively by the output current of said discharge device and by said independent source of current.

4. Means for regulating a vapor electric discharge device provided with an anode, a cathode and a control grid, and having alternating potentials applied between said anode and cathode and control grid, with a continuous voltage component superposed on the alternating potential between said control grid and cathode, comprising a dynamo-electric machine generating said continuous voltage component, a shunt field winding for said machine, other field-exciting 10 means adapted to vary the total field excitation of said machine, and an independent direct-current generator, said other field exciting means being energized by the output voltage of said discharge device and the voltage of said direct- 15 generator, acting in opposition.

5. The combination of a vapor electric discharge device provided with an energized anode, a cathode and a biased control grid, and a dynamo-electric generator supplying a continuous current component to bias said control grid, a shunt field winding for said dynamo-electric generator, other field windings for said dynamo-electric generator, said other field windings adapted to vary the total field excitation of said 20 dynamo-electric generator, and an independent source of current, said other field windings being energized by said discharge device and said independent source of current, acting in opposition.

6. In the art of vapor electric discharge devices, a dynamo-electric generator supplying a continuous current component of the grid biasing potential, a shunt field winding for said generator, two other field windings for said generator, said other field windings operating differentially to one another, and an independent source of current feeding one of said other differentially operating field windings, the second of said other differentially operating field windings being energized by the rectified voltage of said 40 discharge device.

7. In the art of vapor electric discharge devices, a dynamo-electric generator supplying a continuous current component of the grid biasing potential, a shunt field winding for said 45 generator, two other field windings for said generator, said other field windings operating differentially to one another, and an independent source of current feeding one of said other differentially operating field windings, the second 50 of said other differentially operating field windings being energized by the current output of said discharge device.

8. In the art of vapor electric discharge devices, a dynamo-electric generator supplying a 55 continuous current component of the grid biasing potential, a shunt field winding for said generator, a separately excited field winding for said generator, and an independent source of current, said separately excited field winding being energized by the difference between the rectified voltage of said discharge and the voltage 60 of said independent source.

9. In the art of vapor electric discharge devices, a system of output regulation by variation 65 of the continuous current component of the grid bias potential, comprising controlled generation of said component by a dynamo-electric machine having three field windings, one being a shunt winding, and the other two acting in opposition 70 being energized respectively by the output to be regulated and by an independent source of current.

10. In the art of vapor electric discharge devices, means for regulating a plurality of dis- 75

- charge devices operating in parallel, comprising a dynamo-electric generator supplying a continuous current component of grid-bias potential for one of the discharge devices, a shunt field winding for said generator, two other field windings for said generator, said other field windings operating differentially to one another, one of said other field windings being energized by the output of said one discharge device, and the second 10 of said other field windings being energized by the output of another of said discharge devices.
11. In the art of vapor electric discharge devices, means for regulating a plurality of discharge devices operating in parallel, comprising 15 a plurality of dynamo-electric generators supplying continuous current components of grid-bias potentials for the respective discharge devices, a shunt field winding for each of said generators, two other field windings for each of said 20 generators, said other field windings of each generator operating differentially to one another, one of said other field windings of each generator being energized by the output of the respective discharge-device, and a separate dynamo-electric 25 machine energizing the second of said other field windings of one of said generators, the second of said other field winding of each other generator being energized by the output of the rectifier corresponding to said one generator.
12. In the art of vapor electric discharge devices, means for regulating a discharge device working in parallel with a rotary machine generating continuous current, comprising a dynamo-electric generator supplying a continuous current component of grid-bias potential, a shunt field winding for said generator, two other field windings for said generator, said other field windings operating differentially to one another, one of said other field windings being energized by the 30 output of said discharge device, and the second of said other field windings being energized by said rotary machine.
13. In the art of vapor-electric discharge devices, means for regulating the output comprising 35 a dynamo-electric generator supplying a continuous current component of grid-bias potential, a shunt field winding for said generator, a separately excited field winding for said generator, and an independent shunt-wound generator, said 40 separately excited field winding being energized by the output voltage of the discharge device and the voltage of said independent generator, acting in opposition to one another.
14. In the art of vapor-electric discharge devices, means for regulating the output comprising 45 a dynamo-electric generator supplying a continuous current component of grid-bias potential, a shunt field winding for said generator, a separately excited field winding for said generator, 50 an independent shunt-wound generator, said separately excited field winding being energized by

the output voltage of the discharge device and the voltage of said independent generator, acting in opposition, and a series-wound machine included in the circuit of said independent generator and separately excited field winding and operating as a negative resistance. 5

15. In the art of vapor-electric discharge devices, employed as rectifiers for polyphase alternating current, means for regulating the moment of ignition of the anodes by variation of a 10 continuous current component superposed on the alternating grid-bias potential, comprising a three field winding exciter supplying said continuous current component, said exciter having a shunt field winding and two separately excited 15 field windings acting in opposition and normally balancing out, one of said separately excited field windings being energized by the output of the discharge device, and an independent source of current energizing the other of said separately 20 excited field windings, any tendency to variation of said output affecting the normal balance of said separately excited field windings and causing said exciter to vary the continuous current component applied to the grids in the sense of 25 posing said variation of output.

16. In the art of vapor electric discharge devices, means for regulating a discharge device operating in parallel with another source of continuous current, comprising a dynamo-electric 30 generator supplying a continuous current component of grid-bias potential for said discharge device, a shunt field winding for said generator, two other field windings for said generator, said other field windings operating differentially to one another, 35 one of said other field windings being energized by the output of said discharge device, and the second of said other field windings being energized by the output of said other source.

17. Means for regulating a vapor electric discharge device provided with an anode, a cathode and a control grid, and having alternating potentials applied between said anode and cathode and control grid, with a direct-current voltage component superposed on the alternating potential between said control grid and cathode, comprising a dynamo-electric machine generating said direct-current voltage component, an independent source of direct current, and a plurality of field windings for said dynamo-electric machine, said field windings being energized by the voltage of said dynamo-electric machine, the voltage of said discharge device and the voltage of said independent source of direct current, respectively, and the voltage of said dynamo-electric machine producing shunt excitation and the other last-mentioned voltages acting in opposition to one another as regards the resultant excitation of said machine. 45 50 55
